UNITED STATES PATENT OFFICE

WALLACE N. ROBINSON, OF MINNEAPOLIS, MINNESOTA

GRATING STRUCTURE FOR WINDOWS

Application filed February 18, 1931. Serial No. 516,588.

This invention relates to window or sash construction and more particularly to a grating structure adapted to be attached and associated with a window frame and sash.

It is an object of my present invention to provide an extremely simple, strong and efficient attachment which may be utilized in connection with window frames and sashes for the purpose of providing a protective grating in the window opening when the sash is opened to prevent burglars and prowlers from entering.

More specifically it is an object to provide a grating attachment of the class described which may be easily and quickly installed, which will not mar the appearance of the sash or window frame and which limits the opening movement of the sash as well as provides a grating in the window opening at all open positions of the sash within wide limits.

These and other objects and advantages of the invention will be more fully set forth in the following description made in connection with the accompanying drawing, in which like reference characters refer to similar parts throughout the several views, and in which:

Fig. 1 is a front elevation of the lower portion of a window frame and lower sash taken from the interior of the building, some portions of the sill and wall, as well as the lower rail of the sash being broken away;

Fig. 2 is a vertical section taken on the line 2—2 of Fig. 1;

Fig. 3 is a fragmentary section on a larger scale showing the manner in which the lower ends of the bars are inserted through the sill, and

Fig. 4 is a cross section taken on the line 4—4 of Fig. 3.

In the drawing a window frame of conventional type is illustrated including the sill 5, the parting strips 6 and the ornamental facing 7.

Within this frame the lower sash is slidably mounted in conventional fashion, said sash including the vertical stiles 8 and the lower rail 9, and provided with the usual glazing 10.

I provide a plurality of spaced vertical bars 11 anchored at their upper ends to the rail 9 of the sash and working through vertical apertures 5a formed in the sill 5, preferably directly below the sash rail 9. Bars 11 are constructed of some strong rigid material, such as wrought iron, which is difficult to break or cut, and the bars are preferably arranged and spaced apart to divide the window opening vertically into substantially equal portions.

Spaced vertical sockets 9a are preferably formed or drilled in the lower edge of the sash rail to accommodate the upper ends of the bars 11 and the upper ends of said bars are secured to the sash within said sockets by means of transverse or diametrically disposed bolts 12 the heads of which are preferably disposed at the exterior of the sash. I prefer to connect the upper ends of the bars with an operating handle or lift 13 secured to the medial portion of sash rail 9 and to this end my handle is provided with extended attachment portions 13a which are rigidly bolted to the rail 9 and which further are provided with apertures for receiving the ends of the anchoring bolts 12, said bolts passing through the rail 9, and the upper ends of bars 11, (which may, if desired, be somewhat enlarged as illustrated) and also through the attachment portions of the handle. Nuts 12a threadedly engage the ends of the bolts to secure the related parts. After the nuts have been secured the adjacent ends of the bolts are preferably spread or flattened to prevent subsequent detachment of the nuts.

The lower ends 11a of bars 11 are somewhat reduced in diameter and are provided with toggle bolts or heads 15 which may con-

stitute semi-cylindrical plates medially pivoted to the extremities 11a by relatively heavy trunnions or diametrical pins 11b, the diameter of the cross sectional area of the toggle bolts being equal to or slightly less than the diameter of the body portion of the bar to permit the toggle bolts and lower ends of the bars to be readily inserted through the vertical apertures formed in the window sill. Plates 15 are of such weight and are centrally balanced so that they will normally swing to the horizontal position shown in Figs. 1 and 2 to engage the bottom of the sill and limit the open position of the sash.

It will be apparent that the toggle bolts and lower portions of the bars 11 will be accommodated in the space between the walls of the building and will be entirely concealed from view.

It will, of course, be apparent that if desired the upper sash of the window may be equipped with my protective grating structure, the bars 11 working through apertures in the top board of the window frame.

In operation when the sash is open, bars 11 will be drawn upwardly sliding vertically through the apertured portions 5a and constituting a strong protective grating disposed across the window opening. The opening of the sash will be limited by abutment of the toggle bolts 15 with the sill or member of the frame through which the bars 11 extend.

In recent years burglaries have been frequently perpetrated by gaining admittance to a building through open windows. With my device the window opening is automatically provided with a strong protective grating in all open positions of the sash and it will be impossible for a burglar to gain entrance without demolishing the rails of the sash or the window sill or fracturing the panes or cutting the bars 11, which in any instance requires much labor and difficulty and will cause considerable noise. It is a known fact that in most instances a burglar will not take such chances to gain admittance to a building.

The anchoring of the upper ends of bars 11 to the attachment portions of the handle 13 greatly strengthens the construction and prevents the disconnection of the upper ends of the bars by cutting out small portions of the lower rail of the sash.

From the foregoing description it will be seen that I have provided an extremely simple and highly efficient grating attachment for windows which will exclude burglars and prowlers, which does not mar the appearance of the sash or window frame and which may be very quickly and easily installed in conventional window frames and sashes now in extensive use. The grating is self-adjustable with the opening of the sash. The lower ends of the bars 11 are operatively connected with

the sill or top piece of the window frame as the case may be by merely collapsing the toggle bolt and inserting the bolt and free end of the bars through the vertical apertures provided in the said window frame parts and the toggle bolts will swing to transverse position immediately, providing a lock to prevent the withdrawal of the bars.

It will, of course, be understood that various changes may be made in the form, details, proportions and arrangement of the parts, without departing from the scope of my invention, which, generally stated, consists in a device capable of carrying out the objects above set forth and in the novel parts and combinations of parts disclosed and defined in the appended claims.

What is claimed is:—

1. A grating attachment for windows comprising a plurality of relatively indestructible bars spaced apart to divide the opening of the window and each secured at one end to one of the rails of a sash and slidably working through apertured portions of a member of the window frame and means attached to the free ends of said bars adapted to be collapsed to permit insertion of said ends through said frame member and adapted upon insertion to expand to prevent withdrawal of said bars.

2. In combination with a sliding sash and sill or the like, a series of parallel bars extending in the direction of the opening movement of the sash and having unconnected free ends, means for securing the outer ends of said bars to the rail of the sash, said sill having a series of apertures through which said bars slidably extend and means secured to the inner or free end of each of said bars to prevent withdrawal of said bars upon opening of said sash, said means being contractable to permit insertion of said free ends through said sill.

3. In combination with a sliding sash and sill or the like, a series of parallel bars extending in the direction of the opening movement of the sash and having unconnected free ends, means for securing the outer ends of said bars to the rail of the sash, said sill having a series of spaced apertures therethrough for snugly accommodating said bars, said bars being slidable in said sill, and a retaining element pivoted to the free or inner end of each of said bars and constructed to be swung substantially in alignment with said bars for insertion of said bars through said apertures and to normally be positioned transversely of said bars to abut said sill and prevent withdrawal of said bars therefrom.

4. In combination with a sliding sash and sill or the like, a handle member or lift secured to one of the rails of said sash by attachment means which pass through said rail, a plurality of spaced bars extending in the direction of the opening movement of said sash and having unconnected free ends,

attachment means extending through said handle member and said rail for securing the outer ends of said bars to said rail, said sill having a series of apertures through which 5 said bars slidably extend and means secured to the inner or free end of each of said bars for preventing withdrawal of said bars from said sill, said means being contractable to permit insertion of said free ends through 10 said apertures.

In testimony whereof I affix my signature.
WALLACE N. ROBINSON.
